UNITED STATES PATENT OFFICE.

REUBEN COHN, OF NEW YORK, N. Y.

EAR-PROTECTOR.

SPECIFICATION forming part of Letters Patent No. 397,583, dated February 12, 1889.

Application filed May 2, 1888. Serial No. 272,611. (No model.)

To all whom it may concern:

Be it known that I, REUBEN COHN, a subject of the Emperor of Russia, and a resident of New York, in the county of New York and State of New York, have invented certain new and useful Improvements in Ear-Protectors adapted for Application to Collars, Caps, &c., of which the following is a specification.

This invention relates to means for protecting the ears in cold weather; and its object is to combine with any article of ladies' or gentlemen's wear adapted to receive the same—such, for instance, as collars, caps, capes, and cloaks—ear-protectors that may be brought into position to cover the ears, and when not desired for such use the same may be removed from contact with the ears and then serve as a finish or ornamentation for the article to which they may be applied.

The novel features for which protection by Letters Patent is desired are set forth in the claims at the end of this description.

To enable others interested in the art to understand and make use of my invention, I will proceed to describe the same, having reference to the accompanying drawings, which form a part of this description, and in which like figures of reference indicate like parts in the several views.

In the drawings, Figure 1 shows a side elevation of the bust of a man, illustrating the application of my invention to a fur collar. Fig. 2 is a plan view of a fur collar or cap-band in which my improvements are embodied. Fig. 3 is a side elevation of a cap, showing the manner of applying the invention thereto. Fig. 4 is an edge view of one of the hinged spring devices, and Fig. 5 is a plan view of the same.

Referring to the drawings, 6 designates a fur collar or band of the usual form, and 7 the ear-protecting pieces, which may be formed integral with the collar or band, or may be sewed thereon.

In applying the invention to caps and to ladies' fur garments of various kinds the ear-protecting pieces will be so shaped and attached to the garment as not to be unsightly or bulky when removed from contact with the ears.

The spring device 8 is made, as shown in

Figs. 4 and 5, with a two-part vertical member, 9, embodying the spring-joint 10, and with a curved member, 11, formed integral with or secured to the top of the upper part 55 of vertical member 9.

The several parts of the spring device 8 will be perforated, in order that the device may be secured by sewing to the lining of the garment to which it is applied, and thus prevent 60 its displacement when in use.

The hinge-joint of the spring device 8 is constructed as shown in Fig. 4, its leading peculiarity being its simplicity. The part 12 of the vertical member 9 is broadened, as at 13, 65 and its center cut away, the ends of the two arms thus produced being turned over to form bearings for the journals 14, which are secured to or formed integral with one end of the other part, 15, of the vertical member 9. 70 The journals 14 are located a short distance above the extremity of part 15, whereby a lug, 16, is provided which co-operates with the elastic device 17, the same being of steel and being riveted at an appropriate point to the 75 part 12.

The elastic device 17 may be of one or two parts. As shown, it comprises two pieces, one of which, 18, has its free end bent so as to bear against the part 15, and it co-operates with 80 the lug 16 when folding the spring device 8, while the other piece, 19, has its free end bent so as to press against 18 to increase the strength of the spring-action.

The dotted lines of Fig. 4 are employed 85 merely to enable the construction and operation of the spring device 8 to be more clearly understood.

The curved member 11 of spring device 8 projects outward from the vertical member 9 90 and curves downward at each side of said vertical member in such manner as to provide when covered a concave surface, which is adapted to fit snugly over the ear when the protector is in use. 95

The end 20 of the vertical member 9 may be secured by rivets or otherwise to the metallic piece 21, whose office is to give shape to the collar; but piece 21 is not essential to the operation of the invention, as the spring devices may be sewed directly to the lining 100 without the employment of any stiffening me-

dium, and that plan will be adopted when the invention is applied to collars or caps, which it may be desirable sometimes to put in the overcoat pocket.

5 The manner in which my invention is used is plain from the foregoing description. When the ear-protectors are turned up—in doing which the spring device 8 is unfolded against the tension of the spring-joint 10—the curved 10 member of said spring device snugly surrounds the ear without exerting undue pressure thereupon, and thus holds the protectors in position, so that the movements of the body of the wearer and strong winds are not liable 15 to displace the same. The spring devices are very light, and hence add no material weight to the garment to which they may be applied.

Having thus described my invention, what I claim as new, and desire to secure by Letters Patent, is—

20 1. As an improvement in folding ear-protectors, a spring device consisting of a hinged vertical member having an elastic appliance secured thereto, against the tension of which 25 said hinged vertical member is adapted to fold, and provided at one of its ends with a rigidly-fixed curved member which projects outward and downward at both sides of said vertical member, and which when covered provides a concave surface adapted to snugly fit over the ear, substantially as set forth.

25 2. As an improvement in folding ear-protectors, a spring device embodying a vertical member consisting of two parts, 12 and 15, one of which, 12, is broadened, as at 13, and has its center cut away, the ends of the two

arms thus produced forming journal-bearings, as shown, and the other part, 15, provided with journals 14 and lug 16, and an elastic device, 17, secured to part 12 and co-operating with lug 16, substantially as set forth. 40

3. A garment for ladies' or gentlemen's wear provided with an ear-protecting attachment consisting of a pair of spring devices, each comprising a single vertical member having an 45 elastic appliance secured thereto and hinged near its center, so as to fold backward or downward against the tension of said elastic appliance and provided at one end with a rigidly-fixed curved member which projects outward and downward at both sides of said vertical member and provides a concave surface adapted to snugly fit over the ear, substantially as set forth. 50

4. A garment for ladies' or gentlemen's wear 55 provided with an ear-protecting attachment consisting of the metallic piece 21, which gives shape to the garment, in combination with a pair of spring devices appropriately secured to said garment-shaping piece and each consisting of a hinged vertical member provided at one of its ends with a curved member which projects outward and downward at both sides of said vertical member, substantially as 60 set forth. 65

Signed at New York, in the county of New York and State of New York, this 3d day of April, A. D. 1888.

REUBEN COHN.
